[57] CLAIM

The ornamental design for a combined pump dispenser and cap, as shown and described.

DESCRIPTION

FIG. 1 is a top front perspective view of a combined pump dispenser and cap showing our new design; FIG. 2 is a front elevational view thereof;

FIG. 3 is a right side elevational view thereof, the undisclosed opposite side being a mirror image;

FIG. 4 is a top plan view thereof;

FIG. 5 is a bottom plan view thereof;

FIG. 6 is a rear elevational view thereof;

FIG. 7 is a front elevational view shown without the cap for clarity of illustration; and,

FIG. 8 is a top plan view of FIG. 7.

FIG. 2

FIG. 5

FIG. 6

FIG. 7

FIG. 8
